COMBINATION HYDRAULIC CRANE AND CHASSIS

William L. Lowe, Hagerstown, Md., assignor to Grove
Manufacturing Company, Shady Grove, Pa., a corpo-
ration of Pennsylvania

Filed Feb. 26, 1969, Ser. No. 15,925

Term of patent 14 years

Int. Cl. D12—05

U.S. Cl. D14—3

FIG. 1 is a side elevational view of a combination hydraulic crane and chassis showing my new design, with the boom shown in traveling position;

FIG. 2 is a top plan view thereof;

FIG. 3 is a side elevational view showing the opposite side of the crane from that shown in FIG. 1;

FIG. 4 is a front elevational view thereof; and

FIG. 5 is a rear elevational view thereof.

The elements shown in broken lines are included for illustrative purposes only.

I claim:

The ornamental design for combination hydraulic crane and chassis, substantially as shown and described.
